UNITED STATES PATENT OFFICE.

WILLIAM A. HORRALL, OF COLORADO SPRINGS, COLORADO, ASSIGNOR OF ONE-FOURTH TO THEODORE H. PEABODY, ONE-FOURTH TO WILLIAM F. CARROLL, AND ONE - FOURTH TO JOHN M. HARNAN, OF COLORADO SPRINGS, COLORADO.

MAIL-BAG CATCHER AND DELIVERER.

No. 831,438.

Specification of Letters Patent.

Patented Sept. 18, 1906.

Application filed June 15, 1906. Serial No. 321,928.

To all whom it may concern:

Be it known that I, WILLIAM A. HORRALL, a citizen of the United States, residing at Colorado Springs, in the county of El Paso 5 and State of Colorado, have invented a new and useful Mail-Bag Catcher and Deliverer, of which the following is a specification.

This invention relates to mail-bag catchers of a type disclosed in my United States Patent No. 756,498, dated April 5, 1904.

The objects of the invention are to improve and simplify the prior construction, particularly in regard to the bag-delivery means on the car.

15 A further object of the invention is to provide simple means for reversing the deflector-frame, so that it will operate properly when the car is moving in either direction.

With the foregoing and other objects in view, which will appear as the description proceeds, the invention resides in the combination and arrangement of parts and in the details of construction hereinafter described and claimed, it being understood that changes 25 in the precise embodiment of invention herein disclosed can be made within the scope of the following claims without departing from the spirit of the invention or sacrificing any of its advantages.

30 In the accompanying drawings, forming part of this specification, Figure 1 is a perspective view showing a portion of a car and a portion of a road-bed equipped with the improvements of the present invention. Fig. 2 is a detailed plan view of the deflector-frame.

Like reference letters and numerals indicate corresponding parts in the different figures of the drawings.

35 The mail-bag crane which I prefer to use (designated generally by A) consists of a lower section 1 and an upper section 2, said sections being suitably hinged together, as indicated at 3, and provided with a locking device 4, which may be of any suitable form 45 and construction.

The lower section 1 instead of being embedded in the ground, as usual, preferably is fitted into a mail-bag receptacle B and is suitably secured thereto by means such as the 50 bolts 6. It is one of the objects of my inven-

tion to secure the mail-bag receptacle either to the sleepers of the road-bed or to one of the steel rails. The means which I employ for combining the receptacle B with the road-bed consists of a horizontal flange 7, which 55 extends over the adjacent sleepers 8 of the road-bed and is suitably secured thereto by means such as the bolts 9, said flange being also secured to the steel rail 13 by means of the bolts 14.

It will be understood that mail-catching devices are usually installed at a large number of small stations along a railway. For this reason it is of course desirable that the mail-catcher be installed at the lowest possible cost. In using my improved arrangement, wherein the crane A is mounted in the receptacle B and said receptacle B is suitably combined with or attached to the road-bed, by which is meant either the sleepers or 60 the steel rail, or both, it is found that the cost of installing the mail-catcher is materially reduced, as the receptacles and cranes can be manufactured at one central point and shipped to their destination, after which 65 it is only necessary to spike or bolt the receptacle B to the road-bed, as shown.

The upper section 2 of the crane A is provided with an inwardly-extending bag-sustaining arm 10, which is provided with oppositely-extending bag-receiving fingers 11. The upper section 2 is also provided with a suitable cam member 12, the forward edge of which preferably is V-shaped in form.

The mail-car, which is designated generally by C, is formed with the usual side opening or door 16. Secured to opposite sides of the door 16 is a pair of brackets 17 18, having perforated end lugs 19. Pivots connected with one of the brackets 17 18 is a curved deflector-frame, (designated generally by D,) 90 said frame being readily detachable from the bracket by the withdrawal of the pivot-bolt 20. The brackets 17 and 18 constitute means for securing the deflector-frame to 95 either side of the car-door, it being apparent that by withdrawing the bolt 20 the frame can be reversed and secured to the other side of the car-door whenever the direction of movement of the car is changed. The de- 100

reflector-frame, therefore, is readily reversible, as will be apparent. The preferred means for holding the deflector-frame D in outward or inward position, or, in other words, in operative or inoperative position, consists of a 5 bracing member E, which is formed in two sections 21 22, hinged together at 23. At its outer end the bracing member E is detachably connected with the deflector-frame D, as indicated at 24, and at its inner end it is secured in one or the other of a pair of sockets 25, formed in the upper end of the door-frame, a fastening device, such as a bolt 26, being employed for securing the inner end of the 15 bracing member E in either one of the sockets 25 which constitute means for adjustably securing the inner end of the bracing member E to the car-door frame.

The means for delivering a mail-bag from 20 the car to the receptacle B preferably comprises a delivery-cage F, which is carried by the inner side of the deflector-frame D, and preferably consists of an approximately semicircular plate 30, having a slot 31, the opposite ends of the plate 30 being suitably secured to the inner side of the deflector-frame D. Adjacent the delivery-cage F the deflector-frame is formed with a suitable slot 32, through which extends the bent end 33 of a 25 releasing device G, which is pivoted at 34 on the outside of the deflector-frame D and is provided with a forward-bent end 35, which acts as a cam portion to contact with the cam member 12 on the crane A, so as to be 30 pushed toward the deflector-frame D, whereby by the bent end 33 is withdrawn outward from the delivery-cage F. The forward end or cam portion 35 of the releasing device G preferably is squared or broadened at its forward end, so that it will be sure to engage the cam member 12 and be operated thereby.

The deflector-frame D preferably is formed with the large cut-away portions 36 to decrease its weight and is also provided with 45 small slots 37, which are adapted to be engaged by the forward end of the bracing member E when the deflector-frame is in one position or the other, as will be understood. The forward end of the bracing member E 50 when projected through one or the other of the slots 37 is provided with a removable cotter-pin 38, said bracing member E having oppositely-extended projections 39, which bear against the inner side of the deflector-frame D. It will be understood that when it 55 is desired to reverse the deflector-frame the bolt 20 is withdrawn, together with the cotter-pin 38, and the deflector-frame is turned upside down and connected with the bracket 60 on the opposite side of the car-door. The bolt 26 at the inner end of the bracing member E is then removed from one socket 25 and engaged with the other socket 25, so as to change the position of the inner end of the bracing member 65 with relation to the deflector-frame.

The outer end of the bracing member E is of course fitted into the other slot 37 and secured therein by means of the cotter-pin 38, as shown.

When the device is in operation, the mail-bag which is intended for delivery to the car is placed upon one of the bag-receiving fingers 11, and the bag which is intended for delivery from the car is fitted by the mail-clerk up into the delivery-cage F, and the ring at its upper end is engaged by the bent 70 end 33 of the releasing device G so as to hold the bag in suspended position. As the car moves by the crane A the deflector-frame D strikes one bag and deflects or throws it into the car, and the cam member 12 at the same time engages the cam portion 35 of the releasing device G, so as to release the bag in the delivery-cage F and permit it to drop into the receptacle B. The cam portion 35 is normally 75 pressed outward by means of a spring 40.

The improved arrangement of the mail-bag-catching mechanism herein disclosed is strong, simple, durable, and inexpensive in construction, as well as thoroughly efficient 80 in operation.

In the following claims the expression "road-bed" is intended to mean either the sleepers or steel rail, or both.

What is claimed is—

1. In a mail-bag catcher, a mail-bag receptacle having a member projecting from one side thereof and secured to the road-bed and a crane connected with said receptacle.

2. In a mail-bag catcher, a mail-bag receptacle having a flange projecting over the road-bed and connected therewith, and a mail-bag crane connected with said receptacle.

3. In a mail-bag catcher, the combination of a crane having a cam member and bag-receiving fingers, a car having a deflector-frame, a delivery-cage, and a bag-releasing device adapted to be actuated by contact with the cam member on the crane.

4. In a mail-bag catcher, the combination with a car, of a reversible deflector-frame having a slot, a slotted delivery-cage connected with the inner side of the frame, and a releasing device pivoted on the outer side of the frame and having a bent end extending through the slot of the frame and the slot of the delivery-cage, said releasing device having a cam portion at its forward end.

5. A mail-bag catcher comprising a crane 120 having a cam member and bag-receiving fingers, a car having a door-opening, a curved deflector-frame, means for securing the deflector-frame to either side of the door-opening, a bracing member adapted to be connected with either the upper or the lower edge of the deflector-frame, means for adjustably securing the bracing member to the car-door frame, a delivery-cage secured to the inner side of the deflector-frame, and a 125

130

releasing device pivotally connected with the outer side of the deflector-frame and having a bent end extending through the deflector-frame and delivery-cage, and a flared cam portion at its forward end adapted to be engaged by the cam member of the crane.

5 In testimony that I claim the foregoing as

my own I have hereto affixed my signature in the presence of two witnesses.

WILLIAM A. HORRALL.
